UNITED STATES PATENT OFFICE.

THOMAS NEILSON, OF LONDON, ENGLAND.

VALVE AND DEFLECTOR OF VENTILATING APPARATUS.

1,343,576.

Specification of Letters Patent. Patented June 15, 1920.

Application filed January 17, 1920. Serial No. 352,222.

To all whom it may concern:

Be it known that I, THOMAS NEILSON, a subject of the King of Great Britain, residing at London, England, have invented 5 certain new and useful Improvements in and Connected with Valves and Deflectors of Ventilating Apparatus, of which the following is a specification.

This invention has reference to ventilating valves of the hit and miss type in conjunction with which deflectors are employed for directing air currents through the valve in their passage through air trunks and other connections, the invention having special reference to that type of valve wherein the deflector is moved when the valve is operated to the open or closed positions.

In valves of the above type a movable apertured member is disposed between similar stationary members or plates and the movable member is actuated to the open or closed position through the medium of means actuated by a key or its equivalent.

The object of this invention is to provide improvements in combined valves and deflectors of the above character with the effect of producing a combined device of simplified construction with an improved means for effecting the operation of the parts.

According to this invention, a ventilating valve fitted with a deflector has a movable part which comprises two similar plates or halves provided with ears or lugs 35 with which engages a central lever or bar mounted on a spindle adapted to be operated by a key or equivalent means.

In the preferred form embodiment of this invention the deflector is actuated about 40 a pivot pin or hinge by means of a link connection between the deflector and an arm on the said key spindle.

The movable members of the valve are so disposed between the apertured plates 45 that the ear pieces or lugs are adjacent each other, and are engaged by the ends of the said bar, the oscillation of which serves to move the two members nearer to or farther from each other, and in so doing, open or 50 close the valve.

A combined valve and deflector constructed according to this invention is illustrated in the accompanying drawings, wherein—

55 Figure 1 is a plan view of the valve taken from the opposite side thereof to that on

which the deflector is mounted, and with a part of the outer plate broken away.

Fig. 2 is a section taken on the line 2—2 of Fig. 1.

Referring to the drawings, *a* designates the movable plates or members of the valve, each of which are of similar shape and provided with apertures *b*. The inner ends of these plates are formed with lugs or ears 65 *c*, recesses *d* and cut back shouldered portions *e*. The plates are so disposed relatively to each other that the cut back portion of one plate is opposite the lug or ear of the other plate, and thus allows greater freedom 70 of movement relatively to each other than if such cut back part was absent. The recesses *d* in the plates are oppositely disposed and receive the ends of a bar or plate *f* attached to the spindle *g*. The bar or plate *f* serves 75 as a double lever to the spindle and operates the plates *a*.

The plates *a* are mounted between known forms of stationary apertured plates *h*, *j* within a ring plate *k*, the latter serving as 80 a spacing means between the plates *h*, *j* for the free working of the plates *a*.

The spindle *g* is inclosed within a key box *l* attached to the plate *j*, and is provided with a squared or equivalent part *m* 85 on which the bar or plate *f* is mounted, as well as the arm *n* which is connected by a link *o* to a lug *p* on the deflector plate *q*. The deflecting plate *q* is pivotally mounted on the pin *r* supported in the brackets *s* 90 attached to the plate *h*.

It will be obvious from the construction described above with reference to the drawings, that a quick acting and definite operating means is provided for both the valve 95 and the deflector plates, both being actuated by levers attached to the spindle *g*. The bar or plate *f* serves as a central lever between the two halves constituting the movable valve plate, such bar being of a similar 100 thickness to such halves.

I declare that what I claim is:—

1. A ventilating valve of the hit and miss type having a deflector pivoted thereto, a divided movable plate within the said valve, 105 consisting of two similar plane parts having slots adapted to be moved into register with similar openings in the fixed portion of the valve, a pivoted member disposed centrally of the said valve and connected 110 on one side of its axis with the adjacent extremity of one of said plane parts and on

the opposite side of the axis with the other of said plane parts, and having an additional arm substantially integral therewith connected to the said deflector so that on 5 rotation of said pivoted member a separating or meeting movement of said similar parts is effected with a simultaneous movement of the deflector.

- 10 2. A ventilating valve of the hit and miss type having a deflector pivoted thereto, a divided movable plate within the said valve, said plate consisting of two similar plane parts having hooked recesses at the adjacent extremities and slots adapted to be brought 15 into register with similar openings in the fixed portion of the valve, a pivoted member disposed centrally of the said valve, arms on said member to coöperate with said hook shaped recesses, and a third arm connected by a link to said deflector, so that on 20 rotation of said pivoted member a separating or meeting movement of said similar plane parts is effected, and a simultaneous movement of the deflector.
- 25 3. A ventilating valve of the hit and miss type having a deflector pivoted thereto, a

divided movable plate within the said valve, said plate consisting of two similar plane parts having hooked recesses at the adjacent extremities, and slots adapted to be brought 30 into register with similar openings in the fixed portion of the valve, a solid link member connecting said hook shaped recesses, pivoted between them and centrally of said ventilating valve, the pivotal axis of said 35 solid link member having an extremity protruding into a cup member disposed on one side of the ventilating valve, the other extremity of said pivotal axis protruding on the deflector side of the said ventilating 40 valve and formed with an arm, said arm being connected to said deflector by a link member, so that on rotation of the said pivotal axis the rigid link is turned to effect a separating or meeting movement of said 45 plane parts and the required registration of the slots therein with the slots in the fixed portion, and a corresponding and simultaneous movement of the deflector.

In testimony whereof I affix my signature. 50

THOMAS NEILSON.
